PROCESS FOR TREATING OILS

Joseph A. Campbell, Jr., Manhattan Beach, Calif.,
assignor to Union Oil Company of California,
Los Angeles, Calif., a corporation of California

Application September 25, 1934, Serial No. 745,416

6 Claims. (Cl. 196—18)

The present invention relates to an improved process for separating asphalt and/or wax from petroleum oils. The invention relates particularly to a process for producing lubricating oil by separating impurities such as asphalt and/or wax from oils containing the same.

It has been discovered that when a waxy oil is commingled with a solvent or diluent at a reduced temperature, say 0° F. to—40° F., the waxy oil becomes crystallized or solidifies to form a congealed mass of oil and wax. Upon continued contact of the solidified oil and wax such as takes place when the solidified particles settle gradually to the bottom of the container of chilled solvent, solution of the oil in the resulting solvent takes place corresponding to a leaching out of the oil fractions from the wax matrix leaving the wax particles undissolved. This process distinguishes from former practice in that instead of the wax and oil being first dissolved in the diluent and the wax subsequently crystallized out of solution, the waxy oil is first solidified and solution of the oil takes place so that the oil is leached from the wax without dissolving any material portion of the wax. The wax, for the most part, is obtained in a large or coarse flake-like form which readily settles out or filters and hence reduces the mechanical difficulties normally encountered from fine dispersion of wax. A small amount of the crystallized wax may remain in suspension but this can be easily removed by filtration.

The rate of waxy oil introduction into the cold solvent is extremely important since if the rate is too rapid, the sprayed solidified oil and wax will tend to ball up or agglomerate into large masses from which the oil is leached with great difficulty. The rate of waxy oil introduction into the cold leaching solvent will depend largely upon the temperature of the waxy oil when introduced into the leaching solvent or in other words, the rate will depend upon the viscosity of the waxy oil at the temperature of introduction into the solvent. As will be pointed out, oils having low viscosities at the temperature of introduction into the cold leaching solvent crystallize as spongy masses which agglomerate readily at the top of the leaching column. This spongy mass descends or settles rather slowly through the leaching solvent. Such oils must necessarily be introduced rather slowly in order to permit proper leaching and to prevent accumulation and agglomeration at the top of the column. Oils having high viscosities at the temperature of introduction into the leaching solvent crystallize as strings or pel-

lets which descend rapidly through the solvent. These oils may be introduced at a greater rate than the oils of low viscosity provided the height of the column is sufficient to provide adequate leaching of the occluded oil from the crystallized wax.

The rate of oil introduction cannot be given in exact figures since this will depend upon the size or height of the leaching column, the ratio of solvent to waxy oil and the character of leaching solvent and waxy oil. However, the rate may be readily determined by anyone skilled in the art. When using liquid propane at a temperature of —40° F. as the leaching solvent in a ratio of approximately 5 volumes of the propane to one of the waxy oil, I have found that it requires approximately one hour for the solvent to thoroughly leach out the occluded oil from the wax matrices. Therefore, if the propane is introduced countercurrent to the waxy oil at a rate of 200 barrels per hour, the oil should be sprayed into the top of the leaching column at a rate of not in excess of forty barrels per hour in order to provide a leaching time of one hour. In the particular case, the oil sprayed had a viscosity of less than 500 seconds Saybolt Universal at 100° F. and the waxy oil solidified in flaky form when sprayed into the cold solvent. It is obvious that if the oil had been solidified, by the leaching solvent as strings or pellets, the leaching time would be greater. Also, if the propane to oil ratio were increased, the leaching time would be decreased. Propane has a high solvent power for oil at low temperatures; obviously, therefore, by using other solvents not having as great a solvent power for oil at low temperatures as propane, the leaching time and/or solvent to oil ratio would necessarily be increased to give proper washing of the crystallized wax.

As indicated above, the occluded oil in the crystallized particles is gradually leached from the structure as the particles settle to the bottom of the leaching column. The wax structure remains practically in the shape as when the waxy oil is first crystallized at the top of the column. However, due to the fact that the cementing oil is removed, the crystallized wax particles are extremely fragile and will break into finely divided particles if the same are subjected to severe agitating conditions. Such finely divided wax particles are difficult to separate from the oil by such means as settling or filtering.

It is thus important to prevent substantial working of the solidified particles at the top of the leaching column so as to prevent agglomera-

tion and at the bottom after the oil has been leached out of the crystallized structure so as to prevent rupture of the crystallized wax particles.

Preferably the oil is introduced into the cold

- 5 solvent in such manner that leaching of the oil by the solvent takes place rapidly. If the oil is introduced into the cold solvent as a spray or fine streams, solidification takes place upon the surface of the cold solvent as flat buttons or flakes. The solvent may then readily dissolve out the oil from the solidified particles leaving wax matrices which have been thoroughly washed from oil and which settle rapidly to the bottom of the decanter in which the leaching operation
- 10 takes place. The size of the solidified waxy oil particles will, of course, depend upon the leaching conditions desired, that is, the time desired to complete the leaching operation, which will in turn depend upon the character of the waxy oil
- 15 and the solvent to oil ratio during leaching. Preferably, however, the size of the solidified oil particles should not be too thick, since the leaching time increases considerably. I have found that sufficiently rapid leaching will be obtained when
- 20 the waxy oil is solidified in thicknesses substantially not greater than $\frac{1}{4}$ in. at its smallest dimension. I may solidify the waxy oil as flat buttons or flakes or pellets $\frac{1}{4}$ in. thick or as long strings $\frac{1}{4}$ in. in diameter or even as sheets $\frac{1}{4}$ in. thick.
- 25

While I may operate by spraying the oil at a low viscosity directly into the refrigerating diluent, I preferably operate in such manner as to first obtain good crystallization of the wax in the oil and follow this by leaching out the occluded oil. I may accomplish this by chilling the oil, for example, to below its pour point in the absence of a diluent and subsequently spray or otherwise introduce the crystallized wax and oil into the cold leaching diluent. If desired, the waxy oil may be subjected to a digesting operation at a low temperature preferably at a temperature below the pour point of the waxy oil so as to permit good crystallization of the wax in the oil and subsequently leach out the occluded oil. The leaching temperature or temperature of the leaching solvent may then be either at the temperature of digestion or slightly below. By operating in this manner substantially little or

50 no wax will be dissolved in the leaching diluent and thus less difficulty will be encountered with subsequent recrystallization of wax in finely dispersed form and effects of solvation of oil in the wax.

55 Another method for preparing the waxy oil prior to leaching resides in chilling the waxy oil to below its pour point, then working the waxy oil to break up the gel and form a fluid mass and repeating this operation of chilling and breaking up the gel until substantially all of the wax has been crystallized into good wax crystals. This mixture may then be sprayed or introduced as small particles into the cold leaching solvent. It will be observed that when the waxy oil is chilled

60 to below its pour point, a portion of the wax crystallizes out of the oil and the mass becomes a gel. This gel may be made readily fluid again by working such as by gently stirring the mass. However, when the gel is broken, the crystallized

65 wax will not redissolve in the oil. By repeating this operation of chilling to say a lower temperature, the mass will again become a gel forming new wax crystals which may again be broken or rendered fluid by further working. After a number of such operations of chilling and breaking

70 the gel, the wax present in the oil may be substantially all crystallized into large wax crystals. This mixture may then be sprayed or otherwise introduced into the cold leaching solvent.

75 It has been observed that the character of the waxy oil regarding its viscosity at the temperature of introduction into the cold leaching solvent and also the character of the leaching solvent itself influences the character of crystallization in the solvent. However, when employing normally liquid or substantially non-volatile solvents such as casinghead gasoline, hexane, pentane and the like, an oil of any viscosity whether high or low, will crystallize in the cold leaching solvent in the form of strings or pellets. 10 On the other hand, when waxy oils are sprayed into highly volatile or liquefied normally gaseous hydrocarbon solvents, for example propane, the viscosity of the waxy oil at the temperature of introduction will determine whether the waxy oil 15 will crystallize as strings or pellets or as a spongy mass. If the viscosity of the oil is low, for example, below 500 seconds Saybolt Universal at the temperature of spraying into the cold leaching solvent, crystallization takes place as a spongy 20 mass. This is perhaps due to the fact that as the sprayed particles contact the cold leaching solvents, the sprayed particles solidify as bubbles containing volatile leaching solvent which burst due to the vaporization of the solvent forming a 25 solidified foam-like substance. When oils of high viscosity, for example, approximately 500 seconds Saybolt Universal or higher at the temperature of introduction, are sprayed into such volatile solvents, crystallization takes place as strings or 30 pellets. The viscosity of the oil can be low, either due to its intrinsic nature or because of predilution with a diluent or because of its being heated to an elevated temperature. The viscosity may be high due also to its intrinsic nature or because of 35 precooling prior to spraying into the cold leaching solvent.

40 Whether a spongy mass or strings or pellets is desirable or not depends upon conditions of the leaching operation. A spongy mass is desirable 45 where conditions of the leaching are quiescent because leaching takes place more rapidly due to the thinner sections of the crystallized oil. Thus, when leaching in solvents of high volatility, it is preferable to maintain the solvent particularly 50 in the lower part of the leaching column in a substantially quiescent state. This may be accomplished by imposing superatmospheric pressure on the solvent during the leaching operation. Pressure may be imposed by introduction of an 55 extraneous gas which is insoluble in the leaching solvent or which will not liquefy at the low temperatures existing in the leaching column. Thus, I may use air, carbon dioxide or other gases under pressure sufficient to suppress substantial boiling 60 of the leaching solvent. I may also suppress substantial boiling at the lower part of the leaching column by controlling the escape of vaporized leaching solvent, such vaporization occurring when the relatively warm waxy oil contacts the 65 cold leaching solvent. Thus, by controlling the operation of a valve positioned on top of the leaching column so as to maintain pressure on the liquid, I may suppress substantial boiling at points below the upper portion of the column. 70 A small amount of boiling at the top of the column is not detrimental to the success of operation of the process particularly when the rate of oil introduction is controlled fairly low so as to prevent agglomeration of crystallized waxy oil. 75

However, agitation must not be severe after a substantial amount of oil has been leached out of the crystallized structure, otherwise the wax crystals will break up into finely dispersed particles which are difficult to separate from the oil solvent solution by settling and the like.

When leaching in solvents of low volatility or substantially non-volatile solvents, the leaching may be accomplished with gentle or slow agitation. This is for the purpose of presenting new surfaces to the leaching solvent and prevent the solidified pellets or strings from massing at the bottom of the leaching column. Gentle or slow agitation is desirable under these conditions for the reason that the crystallized strings or pellets settle rapidly to the bottom of the leaching column and therefore must necessarily be agitated for the purpose of permitting the leaching solvent to dissolve the oil. However, the agitation must not be so severe that the crystallized masses will break up into finely dispersed wax crystals. This precaution is particularly necessary, as stated above, during the last stages of the leaching operation since the leached particles comprise fragile wax crystals substantially in the shape originally crystallized in the solvent but from which the occluded oil has been leached out. Such crystals break readily with substantial agitation into finely dispersed particles whereas when in an unbroken state, the crystals settle readily to the bottom of the decanter. The agitation may be accomplished by providing a stirring device in the leaching column as is well known to those skilled in the art. The stirrer is preferably operated very slowly, merely sufficient to churn the crystallized masses. In a counter-current leaching process where the oil is introduced into the top of a leaching column and solvent at the bottom, the agitation accompanying the introduction of solvent at the bottom of the leaching column may be sufficient to prevent the strings or pellets of crystallized oil from forming large masses to prevent the leaching solvent from producing the desired results.

In general, the character of the leaching solvent is one which has a good solvent power for oil but not for the wax at low temperatures. As leaching solvents, I may employ any of the liquefied normally gaseous hydrocarbons, such as ethane, propane, butane, iso-butane, or mixtures thereof. I may also employ such normally liquid hydrocarbon solvents as pentane, hexane, etc., castinghead gasoline, naphtha, etc. At low temperatures, the hydrocarbon solvents readily dissolve the oil from the crystallized wax oil but dissolve substantially none of the wax. Other solvents which may be employed comprise alcohol, ether, mixtures of alcohol and ether, acetone, benzol or mixtures of acetone and benzol, and chlorinated normally gaseous hydrocarbons such as methylene chloride and dichlorethylene.

When employing liquefied normally gaseous hydrocarbons, the temperature of the leaching solvent is preferably reduced by vaporizing a portion of the solvent under reduced pressure to substantially the boiling point of the solvent. Normally liquid solvents may be chilled by circulating them in indirect heat exchange with a refrigerating medium, such as cold brine or by commingling the normally liquid solvent with a liquefied normally gaseous hydrocarbon such as liquid propane and effect the chilling by vaporizing the normally gaseous hydrocarbon under reduced pressure. To effect the chilling of the normally liquid solvent, other liquefied normally gaseous materials may be

employed such as ammonia, liquid sulphur dioxide, methyl chloride, carbon dioxide and the like which exert a refrigerated effect by reducing the pressure and vaporizing the liquefied normally gaseous material.

Another feature of my invention resides in pre-mixing the waxy oil with wax anti-solvents prior to introduction into the leaching solvent. Thus, I may commingle the waxy oil either at, below or above the pour point of the waxy oil and subsequently spray or otherwise introduce the mixture into the leaching solvent. If desired, I may mix the waxy oil with the wax anti-solvent at a temperature above the pour point of the oil, then precool the mixture to obtain good crystallization of the wax in the mixture and subsequently introduce the chilled mixture into the leaching solvent. I may first obtain the desired crystallization of the wax in the oil and subsequently dilute the chilled oil with a wax anti-solvent and then leach out the occluded oil. As wax anti-solvents I may employ naphtha preferably having a boiling range between 200 and 300° F., alcohols such as methyl, ethyl, propyl or butyl or mixtures thereof, chlorinated light hydrocarbons such as dichlorethylene and trichlorethylene, mixtures of benzol and the like and acetone or other ketones, mixtures of benzol and the like and butanol or other alcohols, liquid sulphur dioxide, aniline, chloraniline, nitrobenzol, dichlorethyl ether, methyl formate, phenol, cresylic acid. Some of these wax anti-solvents are also good leaching solvents as, for example, benzol and alcohol. When using such solvents it may be desirable to mix the waxy oil with a small amount of the solvent, obtain good crystallization by chilling and then effect the leaching in a larger volume of the same solvent. In the case of mixtures of acetone and benzol or toluol as wax anti-solvents, it may be desirable to use acetone, perhaps with small amounts of benzol or toluol, for the predilution and obtaining good crystallization of wax prior to leaching and subsequently effect the leaching in benzol or toluol.

It is thus an object of my invention to accomplish dewaxing of waxy oils by spraying the waxy oil into a cold leaching solvent so as to obtain solidification of the waxy oil and subsequently leach out the occluded oil from the solidified masses to leave a substantially oil-free wax. It is an object of the invention to control the size of the oil stream introduced into the cold leaching solvent so as to obtain crystallized oil particles which may be readily leached by means of the leaching solvent.

An important object of the invention is to employ as leaching solvents, such materials which have a good solvent power for oil but not for wax at low temperatures.

It is a particular object of the invention to employ a liquefied normally gaseous hydrocarbon such as propane as the leaching solvent and to prevent ebullition in the lower portion of the leaching column so as to prevent breaking of the wax matrices into finely dispersed particles. In other words, it is an object of the invention to produce sufficiently large wax crystals or particles which may be readily removed from the oil solvent solution by settling.

It is another object of the invention to accomplish good crystallization of wax in the oil and subsequently leach the occluded oil from the wax by means of a solvent to leave a wax matrix substantially free from oil which may be readily separated from the oil solvent solution by settling.

Another object of the invention resides in commingling the waxy oil with a wax anti-solvent and subsequently leach out the oil by a cold solvent adapted to dissolve the oil but not the wax at a low temperature.

Another object of the invention resides in commingling the waxy oil with a good wax anti-solvent and obtain good crystallization of the wax in the presence of a wax anti-solvent prior to leaching and subsequently leach out the oil from the mixture in the presence of a solvent which has a good solubility for the oil but not the wax.

Other objects and features of my invention will be apparent from the following description of the drawing which is not to be considered as limiting.

Referring to the drawing, the waxy oil in tank 1 at a temperature above its congealing point is withdrawn through line 2 controlled by valve 3 and pumped by pump 4 through line 5 and valve 6 through spray head 7 where it is passed countercurrent to a leaching solvent at a low temperature as will be further described.

Instead of spraying the waxy oil directly into the leaching column, I may first subject the waxy oil to a prechilling operation by closing valve 6 and opening valve 9 on line 10 and passing the waxy oil into mixer or chiller 11 which is provided with a propeller agitator and scraper 12 operated by pulley 14 connected to a suitable source of power not shown. Chamber 11 may be operated either as a mixing chamber or as a chilling chamber or both. Chilling in chamber 11 may be accomplished by expanding a refrigerating material through jacket 15 such as liquefied normally gaseous hydrocarbon as liquid propane withdrawn from storage tank 16 via line 17 controlled by valve 17' and pump 18 which forces the liquid propane through line 20 and pressure reduction valve 29' into jacket 15. The vaporized propane leaves jacket 15 via line 22 and valve 22' and passes into line 23. The temperature in jacket 15 may be controlled by operation of valve 22' which controls the pressure in the jacket. The vaporized propane passing into line 23 from all apparatus in which propane is vaporized is recovered by compressing in compressor 24 where the pressure on the propane gases is increased and then passes via line 25 to condenser 26 where the compressed propane is liquefied which then flows through 27 into propane storage tank 16. Instead of expanding liquid propane into jacket 15 to effect the desired refrigeration, I may expand other liquid materials which are normally gaseous under ordinary temperatures and pressures and which accomplish a refrigeration when expanded. Such materials may comprise liquid ammonia, liquid sulphur dioxide, liquid carbon dioxide, methyl chloride and the like. If desired, I may circulate a cold liquid through the jacket to effect the desired refrigeration. This may comprise the dewaxed cold solvent oil solution prior to removal of the solvent from the oil. If desired, a small amount of the liquefied normally gaseous hydrocarbon may be mixed with the waxy oil and chilling accomplished by vaporizing the solvent under reduced pressure.

The extent of refrigeration of the waxy oil will depend upon the particular conditions under which the operation is desired to be carried out. For example, I may merely chill the waxy oil to slightly above its pour point, say 120° F. for an oil having a viscosity of 240 seconds Saybolt Universal at 100° F. and then spray the waxy oil into the leaching solvent, or I may chill to below

the pour point of the oil as for example, 60° F. prior to the leaching operation. In connection with the latter operation, the waxy oil may be subjected to sufficiently low temperatures to accomplish crystallization of the wax in oil prior to leaching. One desirable method of operation is to effect the precrystallization of wax gradually by chilling to, say the pour point of the oil, 115° F. for example, and obtaining some crystallization of the wax, the oil being substantially in the form of a gel. This gel may be broken by slowly agitating the gel such as by means of agitator 12 to obtain a fluid mass. The partially chilled mass may then be further chilled to a lower temperature than the pour point of the oil, say 40° F. to obtain further crystallization of the wax and gelling of the oil which may again be broken by agitator 12. After substantially all of the wax has been crystallized and the gel broken in such manner as to not obtain substantial disruption of the wax crystals, the mass may be introduced into leaching column 8 via line 28 controlled by valve 28' and pump 29 which forces the chilled mass through spray 7.

If desired, the waxy oil may be gradually chilled without substantial agitation to low temperatures, for example 0° F. to crystallize substantially all of the wax from the oil and allowed to digest at this temperature for a period of time until good crystallization of the wax has resulted. Then it may be commingled with a diluent introduced into mixer 11 via line 30 controlled by valve 30' so as to obtain a fluid porridge-like mass which may be readily pumped through the spray head 7. The admixture of diluent as, for example, naphtha, may be effected by means of agitator 12. However, this admixture is preferably under slow agitation so as not to break the wax crystals.

In leaching column 8, the sprayed oil upon contact with the cold leaching solvent at the top of the leaching column, is immediately solidified and in passing countercurrent to leaching solvent introduced at the bottom of the column, the solidified oil is dissolved in the leaching solvent, leaving a wax matrix at the bottom of the leaching column substantially free from oil.

Where a normally gaseous liquefied hydrocarbon, such as liquid propane, is employed as the leaching solvent in column 8, the liquid propane is withdrawn from propane storage tank 16 via line 17 controlled by valve 17' to pump 19 which forces the propane through line 31 controlled by valve 31' into propane chiller 32 where a portion of the liquid propane is vaporized by opening valve 33' on line 33. The vaporized propane being released through valve 33' passes through line 33 into line 23. By reducing the pressure in chiller 32 to substantially atmospheric, the temperature of the remaining propane will be lowered to substantially -40° F. The propane in chiller 32 at -40° F. is withdrawn via line 34 controlled by valve 34' and pumped by pump 35 into the bottom of the leaching column 8 via a perforated spider 36.

The amount of leaching solvent introduced into the column 8 will depend upon the character of the solvent and the character of the waxy oil. I have obtained good results when using a liquefied normally gaseous hydrocarbon, such as liquid propane, as the leaching solvent with as low as four volumes of the propane to one of the waxy oil. However, by employing larger amounts of propane, say up to ten volumes of the propane to one volume of the oil, the leaching of the oil

from the solidified oil and wax will take place more readily. It is not economically desirable to employ more than ten volumes of the propane due to the large capacity of leaching columns required to effect the leaching operation.

When employing a liquefied normally gaseous hydrocarbon such as propane as the leaching solvent, a portion of the solvent will vaporize immediately upon contact with the oil, creating a turbulent condition in the column. This is not desirable since the leached wax matrices are readily disrupted by any substantial agitation forming finely dispersed wax particles which are difficult to separate from the oil solvent solution by settling. It is, therefore, preferable to maintain quiescent leaching conditions and prevent substantial boiling particularly at points below the top of the leaching column. Substantial boiling may be prevented by controlling the vaporization of the solvent such as occurs when the relatively warm oil contacts the leaching solvent. This vaporization will create a pressure in the column which will suppress tendency of the leaching solvent to boil in the lower portion of the leaching column. The pressure may be controlled by means of valve 31' on line 31. Vapors removed from the leaching column pass via line 31 into line 23. If desired, the boiling in the leaching column may be substantially prevented by superimposing a gas in the leaching column which is substantially insoluble in the oil and propane. This gas may be introduced via line 38 controlled by valve 38' and may comprise air, carbon dioxide or other non-miscible gas. It is desirable to prevent infiltration of heat from the outer walls of the leaching column since this causes the normally liquefied gaseous hydrocarbon or leaching solvent to boil in the column. One method for preventing this is to provide a jacket 39 around the column and circulate a cold medium through the jacket, the cold medium being at or preferably below the temperature of the contents in the column. Another method resides in taking propane under superatmospheric pressure from storage tank 16 and expanding it into the jacket via line 17, pump 19, line 40 and expansion valve 40'. The expanded gases leaving the jacket via line 41 are passed into line 23 via line 50. If desired, I may expand ethane or a solvent having a lower boiling point than the temperature of the leaching solvent so as to provide a temperature in the jacket lower than that existing in the column.

The leached wax matrices accumulating at the bottom of the leaching column and which have been thoroughly washed by means of the fresh propane introduced via line 34 and spider 36 are withdrawn from the column by means of gear pump 45. The removal of the wax matrices from the column is aided by paddle 42 on shaft 43 which is rotated by pulley 44 connected to a suitable source of power not shown. The paddle 42 is turned very slowly, merely sufficient to gently agitate the wax slurry accumulating at the bottom of the column and to pass the wax slurry to gear pump 45. Gear pump 45 forces the wax through line 46 controlled by valve 46' into evaporator 47 where the small amount of propane occluded in the wax is vaporized by the aid of steam circulated through closed coil 48. The vaporized propane passing through mist extractor 49 is withdrawn from the column via line 50 controlled by valve 50' and passed into line 23. The wax at the bottom of the evaporator substantially free from entrained propane is with-

drawn via line 52 controlled by valve 52' and sent by means of pump 54 through line 55 into wax storage tank 56. The solution of oil and propane carrying a small amount of entrained crystalline wax which had not settled to the bottom of the leaching column is withdrawn via line 57 controlled by valve 57' and pumped by pump 59 via line 60 through filter 61 where the entrained precipitated wax is separated and removed via line 62 controlled by valve 62' and pump 64 which introduces the wax into line 46 and evaporator 47 where the propane is vaporized. If desired, this wax may be recovered separately in which case the wax slurry will be passed into a separate evaporator.

The clear solution is then passed through line 65 through heat exchanger 66 where the temperature of the clear solution is raised, after which the preheated solution passes via line 67 into evaporator 68. If desired, the cold propane oil solution may be circulated through jacket 15 of mixer 11 to effect the cooling of the incoming oil and then passed into evaporator 68. The propane in evaporator 68 is vaporized, aided by steam circulating through closed coil 69. The vaporized propane passing through mist extractor 70 is withdrawn via line 71 controlled by valve 71' and sent into line 23. The wax free oil is withdrawn from the bottom of the evaporator via line 73 controlled by valve 74 and pumped by pump 75 into dewaxed oil storage tank 16.

As stated above, the vaporized propane collecting from all apparatus in line 23 is sent to compressor 24 where the pressure on the propane gases is raised, after which it is liquefied in condenser 26 and returned to propane storage tank 16.

The foregoing description of the drawing has been made with reference to carrying out a process of dewaxing without aid of wax anti-solvents. Wax anti-solvents, such as liquid sulphur dioxide, or a mixture of acetone and benzol or toluol or any of the wax anti-solvents herein mentioned, may be used to aid conditioning the waxy oil prior to the leaching operation. Such wax anti-solvents may be mixed with the waxy oil in a mixing tank 11 and are withdrawn from storage tank 17 via line 78 controlled by valve 78' and pumped by pump 80 through line 81 into the mixer 11. If desired, the wax anti-solvents may be mixed directly with the oil at a temperature above the pour point and then sprayed into the leaching column, or after admixture with the waxy oil, the mixture may be cooled by any of the methods herein described to a temperature at or below the pour point of the oil so as to obtain good crystallization of the wax prior to the leaching operation. The chilling may be accomplished in such manner as stated above, that is, chilling the oil to form a gel and working this gel to break it up and form a fluid mass which may then be pumped into the leaching column. Preferably, however, the waxy oil is chilled to obtain the crystallization of the wax and subsequently commingled with the wax anti-solvent or the waxy oil may be first chilled to obtain partial crystallization of the wax and then mixed with wax anti-solvent and further chilled to obtain further crystallization of the wax and subsequently passed into the leaching column.

When employing wax anti-solvents, it is desired to recover the wax anti-solvents from the dewaxed oil and from the separated wax as a separate fraction from the diluent employed. This may be accomplished by condensing the va-

porized diluent and wax anti-solvent in evaporators 47 and 68 to obtain condensation of the wax anti-solvent if such has a higher boiling point than the diluent or condensation of the diluent if the boiling point of the diluent is higher than that of the wax anti-solvent and then collecting the condensate as a separate fraction. The unvaporized material may then be liquefied by compression and cooling if this material comprises a liquefied normally gaseous hydrocarbon diluent.

The following represent examples of the operation of the portion forming the subject matter of my invention:

Example 1

15. A raffinate produced by extracting a waxy distillate with a mixture of liquid sulphur dioxide and benzol and having an A. P. I. gravity of 31.5°, a viscosity of 50 seconds Saybolt Universal at 210° F., a pour point of 120° F. and a wax content of approximately 25% was sprayed into the cold propane at a temperature of about 125° F. which is slightly above the pour point of the waxy oil. Propane was introduced into the bottom of the leaching column countercurrent to the waxy oil and was at a temperature of -40° F. The amount of propane introduced into the leaching column was in the ratio of about 7 volumes of propane for every volume of waxy oil sprayed into the column. After washing the wax countercurrently in the leaching column and filtering the oil solvent solution decanted at the top of the column to remove a small quantity of suspended wax, the solvent was distilled from the oil, the recovered oil had a pour point of 0° F., and A. P. I. gravity of 29°, a viscosity of 53 seconds Saybolt Universal at 210° F. and was recovered in a yield of 72%. The wax after vaporizing the propane had a melting point of 130° F. and was recovered in a yield of 27%.

Example 2

A raw distillate from a Santa Fe Springs crude having an A. P. I. gravity of 20° and a viscosity of 70 seconds Saybolt Universal at 210° F. and a pour point of 115° F. was chilled to a temperature of 40° F. in a device such as mixer 11 and mechanically agitated to break up the wax gel structure giving a porridge-like mass which was then sprayed into cold propane at -40° F. Propane at a temperature of -40° F. in a ratio of about 5 volumes to one of the waxy oil was introduced into the bottom of the leaching column in the manner heretofore described. A yield of oil equal to 80% of the original was recovered having a viscosity of 74 seconds Saybolt Universal at 210° F. and a pour point of 0° F. The recovered wax had a melting point of 128° F. and was obtained in approximately 20% yield.

Example 3

The same structure as in Example 2 was mixed with an equal volume of a mixture of 50% acetone and 50% toluol and the mixture cooled to 10° F. with slow agitation. This mixture was then passed into cold propane and extracted with 5 volumes of propane at a temperature of -15° F. to one volume of the waxy oil. The recovered oil had a pour point of 5° F., a viscosity of 72 seconds Saybolt Universal at 210° F. and was recovered in a yield of 81%. The wax had a melting point of about 129° F. and was recovered in a yield of about 19%.

The foregoing exemplary description of my invention is not to be considered as limiting since many variations may be made within the scope

of the following claims by those skilled in the art without departing from the spirit thereof.

I claim:

1. A process for dewaxing oils which comprises spraying waxy oil into a cold liquefied normally gaseous hydrocarbon solvent capable of dissolving oil at low temperatures but not substantial quantities of wax, solidifying said sprayed oil by means of said cold solvent to form a plurality of frozen particles of wax and oil, extracting the occluded oil from said frozen particles by means of said cold solvent to leave wax matrices substantially free from occluded oil without dissolving substantial amounts of wax, said extraction being accomplished under superatmospheric pressure sufficient to prevent substantial ebullition of solvent during the extraction of oil from the solidified waxy oil particles, removing the oil solvent solution from the wax matrices and separating the solvent from the oil. 20

2. A process as in claim 1 in which the cold solvent comprises liquid propane.

3. A process for dewaxing oil which comprises spraying a waxy oil into a leaching column containing a cold liquefied normally gaseous hydrocarbon solvent capable of dissolving oil at low temperatures but not substantial quantities of wax and maintained under controlled superatmospheric pressure sufficient to prevent substantial ebullition of solvent upon contact with the waxy oil and to prevent substantial agitation of the wax matrix after substantial quantities of oil have been extracted from the waxy oil by means of said solvent, freezing and solidifying said waxy oil by means of said cold solvent, allowing said frozen oil to contact said cold solvent for sufficient time to permit said solvent to extract occluded oil in said frozen waxy oil and to leave a solidified wax matrix substantially free from occluded oil, separating the oil dissolved in said solvent from the wax matrix and separating the solvent from the oil. 30

4. A process as in claim 3 in which the vaporization of solvent caused by contact of the waxy oil with the solvent is controlled so as to maintain a superatmospheric pressure in the leaching column. 45

5. A process for dewaxing oils which comprises spraying a waxy oil into the top of a leaching column containing a cold liquefied normally gaseous hydrocarbon solvent capable of dissolving oil at low temperatures but not substantial quantities of wax, introducing cold leaching solvent into the bottom of said leaching column, freezing and solidifying said waxy oil by means of said cold solvent, allowing said frozen oil to contact said cold solvent for a sufficient length of time to permit said solvent to leach out occluded oil in said frozen waxy oil and leave a solidified wax matrix substantially free from occluded oil at a lower portion of said leaching column, preventing substantial agitation of said wax matrix in the lower portion of said leaching column, by controlling vaporization of solvent from said leaching column so as to maintain a superatmospheric pressure in said leaching column, removing the wax matrix from the lower portion of the said leaching column and the solution of oil and solvent from the top of said leaching column, filtering said oil solvent solution to remove the entrained wax particles and separating the solvent from the oil. 60

6. The process of separating a hydrocarbon oil-wax mixture into solid constituents and liquid constituents which comprises forming a mass of 75

crystallized wax, oil and solvent liquid in a vessel, displacing oil and solvent liquid from said mass in said vessel by introducing a solvent liquid into one end of said vessel while withdrawing oil and solvent liquid from the other end of said vessel, said displacement being carried out with-

out substantial agitation of the crystallized wax and without separation of oil and solvent liquid from the crystallized wax prior to the introduction of the solvent liquid into said vessel to displace oil and solvent liquid from the mass. 5

JOSEPH A. CAMPBELL, JR.
